METHOD AND APPARATUS FOR X-RAY PHOTOGRAPHY

Harvey Nelson Jackson, San Diego, Calif.

Application September 24, 1932, Serial No. 634,766

3 Claims. (Cl. 250—34)

My invention relates to methods and apparatus for X-ray photography, and relates particularly to a method and apparatus for facilitating X-ray photography of the oral regions.

5 It is an important object of my invention to provide a method and apparatus for simplifying the obtaining of accurate relation of the photographic medium and the X-ray or other similar emanation producing apparatus, so as to reduce 10 the time and effort required, as well as the amount of skill necessary in this form of photography.

Other objects and advantages of my invention will be apparent from the reading of the following description in connection with the drawings, wherein for purposes of illustration I have shown a preferred embodiment of the invention.

In the drawings:

Figure 1 is a general elevational view of the 20 device of the invention being used upon a subject, showing the relation of the emanation producing device thereto.

Figure 2 is a side elevational view of an embodiment of the apparatus of the invention.

25 Figure 3 is a top plan view of Figure 2.

Figure 4 is a plan view of the lower arm of the embodiment.

Figure 5 is a transverse sectional view through 30 one of the brackets showing how the companion arm is removably carried thereby.

Figure 6 is a perspective view of the upper arm.

Figure 7 is a view similar to Figure 1 showing the upper arm removed from the embodiment, the whole being in readiness for the photographic 35 operation.

Referring in detail to the drawings, wherein like numerals refer to like parts throughout the same, the numeral 5 generally refers to a source of emanations such as an X-ray machine having 40 the lens portion 6, and the numeral 7 refers generally to an apparatus for holding the film to be acted upon by the emanations while held in a certain relationship to the lens 6, such relationship having been determined mechanically by 45 moving certain portions of the apparatus.

The apparatus comprises an upper arm 8 and a lower arm 9. The upper arm 8 comprises a removable elongated plate 7 such as a tongue-depressor. A bracket generally designated 10 50 has on each longitudinal edge of its plate portion 11 turned over edges 12, 13, each of which defines a channel for slidably receiving the arm 8. From one end of the longitudinal edges depend triangular members 14 which are traversed by a 55 pivot bolt 15.

The lower arm comprises a similarly formed but shorter arm 9 which has secured to its underside a film support plate 16. It will be observed that the film support plate 16 is attached inwardly of one end of the arm 9 as indicated at 60 17 and that the remainder of the plate is offset away from the underside of the arm 9 so as to provide for receiving a portion of the film 18 frictionally between the adjacent ends of the arm 9 and the plate 16.

65 It will be observed that the arm 9 including the plate support 16 is of less length than the arm 8.

Receiving the opposite end of the arm 9 is a bracket 19 which is substantially similar to the bracket 10. The triangular portions 20 of the bracket 19 are not as widely spaced as the triangular portions 14 of the bracket 10, so as to be capable of being disposed within the triangular portions 14 of the bracket 10.

70 The pivot bolt 15 traverses the engaged triangular portions 14 and 20, while a bolt 22 similarly traverses the triangular portions 14a and 21. The pivot 22 is not adjustable, but the pivot bolt 15 has a head on one end and is threaded on the 75 opposite end so as to receive a clamping finger nut 23 which may be adjusted on the bolt so as to clamp the brackets in selected angular relation with respect to each other.

One or both of the arms 14, 14a of the bracket 80 10 have the lower portions pointed and provided with a straight edge 24 to co-operate with radial 85 graduations 25 which are located on one or both of the arms 20, 21 of the lower bracket 19, and radiate from the pivot bolt 15 or the pivot 22 90 as the case may be.

The upper arm 8 and the lower arm 9 being 95 easily removable from the brackets may be changed for each subject, and sterilized arms substituted therefor for use with the next subject.

I shall now describe the nature of my method and the means by which it is carried out. The purpose of the embodiment herein described and shown, is to enable a person taking X-rays of the teeth in the maxillary or superior jaw, to 100 quickly and accurately determine the proper angle at which to set the X-ray tube so that distortion in the radiogram will be eliminated.

The method and operation of the device are 105 as follows:

As an example let us say it is desired to X-ray an upper front tooth. The X-ray film 18 is held firmly and flatly in the end of the short or lower arm 9 of the device. The patient holds the film 18 and arm 9 against and back of the tooth. In 110

this position the plane of the film 18 is not parallel to the longitudinal axis of the tooth.

To take a radiogram without distortion, the tube rays must be perpendicular to a plane which bisects the angle between the plane of the tooth axis and the film plane. The device will determine that bisecting plane and permit the operator to set his X-ray tube perpendicular to it. It operates in this way when the pointer 24 on the upper bracket 10 points to "1" on the graduated arc 25, the arms of the device are parallel, that is the upper arm 8 is parallel to the film plane. The operator then pivots the upper arm 8 until it is parallel to the longitudinal axis of the tooth and takes a reading on the arc 25. He then moves the upper arm 8 back until the pointer 24 is equidistant between "1" and his last reading. The upper arm 8 is now parallel to a plane bisecting the angle between the film plane and the longitudinal axis of the tooth.

The operator then sets the face of his X-ray tube 6 parallel to the upper arm 8 and may now remove this arm 8 from its bracket 10. The radiogram may then be taken without distortion.

The following are among the advantages of the device of the invention:

1. The device makes possible a standardized technic for making dental radiograms. The film angle, the tooth angle and the mean angle are exactly obtained, and the tube rays may be directed accordingly.

2. By the use of this device both the long axial film plane and the medio-distal film plane are quickly and exactly established outside of the mouth, thus enabling the operator to exactly direct the tube rays at the film.

3. The device prevents the bending of films, thus avoiding distortion of the print.

4. New sterile tongue depressor sticks may be used for each patient.

5. By quickly and certainly establishing the correct mean angle, the device insures pictures of true anatomical proportions and diagnostic value.

6. The device provides a method of real diagnostic value for checking up on all tissue conditions, because the same angle may be used every time if care is taken with the technic.

7. The device enables the operator to obtain a clear picture of the apical areas of the buccal roots of the superior first molars, because the tube angle may be changed for each root with certainty.

8. This device enables the dentist's nurse to take pictures without distortion, thus saving his time.

Although I have shown and described herein a preferred embodiment of the invention, it is to be definitely understood that I do not desire to limit the application of the invention thereto,

and any change or changes may be made in material and structure and arrangement of parts, and in the sequence and the duration of the steps and operations concerned in the method, within the spirit of the invention and the scope of the 80 subjoined claims.

I claim:

1. In a device of the character described, a pair of holder brackets, a hinge connection between said brackets, a direction arm carried by one of said brackets, a film holding arm carried by the remaining one of said brackets, cooperating means on said brackets for indicating the relative angularity of said arms, said film holding arm having means to hold a radiographic film in longitudinal extension beyond one end of said holding arm and against the lingual side of the part to be radiographed at an angle to the axis of said part, said arms being carried by portions of said brackets remote from said hinge connection so that said arms are spaced from each other when brought into parallel relation. 85

2. A device of the character described comprising a pair of holder brackets, pivot means traversing portions of said brackets and hinging them together, arm holding means on each of said brackets, a direction arm removably inserted in the holder means of one of said arms, a film arm removably inserted in the holder means of the remaining one of said arms, cooperating 100 means on said brackets for indicating the relative angularity of said arms, film clamping clip on said film arm for holding a film extending beyond the outer end of said film arm. 90

3. A device of the character described comprising a pair of L-shaped brackets, pivot means traversing foot portions of said brackets and hinging the brackets together, arm holding means on the standard portion of each of said brackets, a direction arm removably secured by the arm holding means of one of said brackets to extend longitudinally of the standard portion thereof, a film arm removably secured by the arm holding means of the remaining bracket to extend longitudinally of the standard portion of the remaining bracket, cooperating means on the foot portions of said brackets for indicating the relative angularity of the direction and film arms, film clamping means on said film arm to position a film against the lingual side of the part to be radiographed, said direction arm being arranged to be capable of being swung into a plane parallel to the plane bisecting the angle between the plane of the axis of said part and the plane of the film and to have the axis of the source of film affecting emanations adjusted at right angles thereto to enable securing an undistorted radiograph of said part. 110
